UNITED STATES PATENT OFFICE

CHARLES HENRI CLAUDEL, OF VEUXHAULLES, FRANCE

CARBURETOR

Application filed April 6, 1927, Serial No. 181,471, and in France December 24, 1926.

The invention relates to carburetors of the type in which the throttling element of the induction passage of the cylinder towards the motor comprises a rotary oscillating plug, controlling at the same time the admission of the carbureted mixture to the motor and the depression upon the spray nozzle, by the down-stream section and by the relation between the downstream and upstream sections respectively. The invention relates more particularly to carburetors of this type with multiple nozzles.

In these carburetors the slow speed spray or jet nozzle is subjected to the variations of the depressions prevailing at the inside of the rotary plug, while the spray or jet nozzle of the full speed mixture is arranged outside of the rotary plug at the upstream side of the section controlling the depression at the interior of the rotary plug. This usual disposition however is defective, because the main spray nozzle, being placed at the outside of the rotary plug, upon opening the slide is subjected too late to the inductive depression; as a result restarting and operating at speeds intermediate between the extreme slow speed and full speed will be unsatisfactory.

One object of the invention is to remove this inconvenience. A first feature consists therein that the full speed spray or jet nozzle as well as the slow speed spray or jet nozzle are both subjected to the depression obtaining within the rotary plug. In this manner, the curves indicating the output of the various nozzles in function of the openings of the plug, instead of being bent in a reverse direction, and thereby causing for the resulting curve of the total output a break and the difficulty of the passage point, are all running in the same direction; it is thus an easy matter to have the resulting curve of the total output describe a continuous and progressive path according to the desired law.

A further object of the invention is to provide a device for the regulators of multiple carburetors feeding certain types of motors, such as aeroplane motors.

The annexed drawings illustrate as examples several embodiments of the apparatus according to the invention. Fig. 1

is a vertical section, Fig. 2 a similar section of an apparatus more particularly adapted for heavy fuels; Fig. 3 is a schematical view illustrating the improvement as applied to the correctors of carburetors in motors 55 equipped with several carburetors.

The carburetor illustrated in Fig. 1 comprises a float feed chamber 1, and a conduit 2 supplying the main spraying calibrated plug 3 mounted within the bottom part of the main diffusing element 4; the main spraying takes place within the chamber 5 of the element 4, in which, while operating normally, the air arriving through the conduit 7 of the orifice 8, enters through the orifices 6, said orifice 8 being adapted to be regulated by means of a screw 9 communicating with the outside by an orifice 10. The emulsion formed within the chamber 5 is flown through the tube 11 entering at 12 the port 13 of the rotary throttling plug 14; the tube 11 acts at the same time as protection preventing the fuel from flowing off after a stop.

The diffusing element comprises an outer tube 15 encircling the emulsion tube 11 and leaving a narrow free space between both tubes; the orifices 16 are regulated by a nut 17 adapted to regulate additional air intermixing with the emulsion upon its outflow through the orifices 12' provided within the tube 15 below the screw connected head 18 of the nozzle. This head 18 carries, mounted upon its base portion, the slow speed diffusing closed tube 19. This closed tube is provided with one or several supply orifices 20 leading the fuel or the emulsion from the chamber 5, and with one or several upper orifices 21 wherethrough, during slow down operation, the air of the port of the throttling plug is allowed to enter the slow speed nozzle. The upper part of the head 18 carries a flexible tube 22 for the slow speed mixture said mixture being mixed with air entering at 21 in the immediate vicinity of the little opened section from the port 13 towards the induction conduit 29 of the engine.

Fig. 24 shows a corrector for the regulation of the section of the admission of the main air; this device can be controlled in any appro-

priate manner for example, by hand, as here illustrated said corrector being formed as a nut which is screwed upon the tube 15.

A slide 25 whereby to vary the section of the main air inlet can also be provided, said slide being actuated by traction exerted upon a rod or cable 26 against the action of a return spring 27.

The slow speed nozzle, being subjected to the depression obtaining within the rotary slide by the upper end of the flexible tube 22, and the main spraying nozzle being likewise subjected to this depression by the orifices 12', it will be seen that the output of both spraying nozzles and that of the corresponding spraying nozzles vary in the same way, and that any break in the curve of the total output, i. e., any irregularity at the point of passage will be prevented.

As illustrated, an auxiliary induction conduit 28 of reduced diameter is provided, receiving the carbureted slow speed mixture at the outlet orifice 23, and flowing the same without impairing its speed of flow within the induction conduit 29, to a point 30 situated symmetrically between the two branches 29' 29" feeding the cylinder group; in this manner the slow speed mixture is evenly divided between these two groups of cylinders; the wall of the main induction conduit next to the outlet 30 of the auxiliary conduit 28 is heated by a heating chamber 31; protruding wings 32 prevent the gaseous vein from flowing along the wall of the conduits 29' and 29", and prevent in this manner any trouble in the operation of the cylinders due to liquid vesicles that might otherwise be formed.

Fig. 2 illustrates a further embodiment of the spray nozzles, more particularly adapted for a motor using heavy fuels. The general disposition is practically the same as that shown in Fig. 1 with the exception that a heating device as hereafter described, is provided between the lower diffusing chamber 5 and the upper orifices feeding the emulsion to the interior of the throttling plug. A helicoidal peripheral ductor groove 34 upon a cylindrical body 35, which latter is also traversed centrally by the slow speed diffusing tube 19, connects the chamber 5 to the upper annular chamber 33 leading to the orifices 12. The helicoidal duct 34 is closed externally by a thin metallic wall 36 enclosing the cylindrical body 35; this wall is placed within a heating jacket 37 which is preferably heated by the exhaust gases arriving through the socket 38 and escaping through 38'. The ducts 39, connecting the outlet of the helicoidal groove to the annular space 33, enter this groove at a certain distance from the external wall 36. It will be seen that with these dispositions the emulsion is centrifugated and highly heated by the wall 36, and

that only the lightest, perfectly diffused parts can escape through the ducts 39.

The admission of secondary air to the orifices 12 is preferably effected by means of a conduit 16' and it is regulated by a suitable valve 17'.

When the motor is equipped with several carburetors feeding a number of cylinders, such as in multi-cylinder aeroplane engines, the conjugated control of the correctors for the emulsion air or the principal air of the various carburetors engenders complications and inconvenience. Heretofore the various correctors of the same type of the several carburetors were connected by mechanical means such as connecting rods, levers, crank shafts, etc. . . These connections complicate the structure due more particularly to the various angles of deviation required to obtain a single control; the various transmission elements giving rise to lost motion, are subjected to fluxions and vibrations so that variations in the correction will necessarily occur between the several carburetors, and following between the several groups of cylinders; the operation of the motor thereby becomes irregular. All these complications and inconveniences are absolutely overcome by means of the improvement described hereafter. This improvement consists in assembling into one single element a series of cocks with a single plug regulating in an absolutely precise and secure manner the various air admissions for the several carburetors. Fig. 3 illustrates this device in a schematic manner. A cock plug 40 with control lever 41 is provided with various ports 42—42'—42", etc. . . which, in cooperation with the orifices of the body of the cock 43, regulate the admission of the air of correction flowing through preferably flexible tubes 44, 44', etc. . . to the desired point of the carburetors feeding the several groups of cylinders. It is well understood that a multiple corrector of this type can be controlled by any appropriate means either manually or automatically.

Various dispositions of the several constituting elements and changes in their construction can be used without departing from the scope of the invention.

Claims:

1. A carburetor for an internal combustion engine provided with an emulsifier consisting of concentric tubes forming two emulsion chambers, one for normal speed and the other for slow speed and with a flexible tube for conducting the slow speed emulsion in the proximity of the outlet, towards the engine, of a throttling element of the plug type, comprising in combination a throttle valve rotating around an axis perpendicular to the longitudinal direction of said emulsifier and an outlet of the normal speed emulsion chamber having an invariable section during the

rotation of said valve and opening into the interior of said valve.

2. In a carburetor for an internal combustion engine comprising an oscillating throttling element of the plug type with a passage therethrough, said element letting in its slow speed position a little opened section towards the engine, and further comprising a main diffusing chamber with feeding means for the fuel and for the primary air, in combination a slow speed nozzle formed by a flexible tube which opens, for the slow speed position of the throttling element in the immediate vicinity of the little opened section towards the engine, at least one tube connecting the diffusing chamber to the passage through said throttling element so as to form main nozzle, and a helicoidal heated groove between the emulsion chamber and the tube forming the main nozzle.

3. In a carburetor for an internal combustion engine comprising an oscillating throttling element of the plug type with a passage therethrough, said element letting in its slow speed position a little opened section towards the engine, and further comprising a main diffusing chamber with feeding means for the fuel and for the primary air, in combination a slow speed nozzle formed by a flexible tube which opens, for the slow speed position of the throttling element in the immediate vicinity of the little opened section towards the engine at least one tube connecting the diffusing chamber to the passage through the said throttling element so as to form main nozzle, and a helicoidal groove between the emulsion chamber and the tube forming the main nozzle, a heating jacket embracing said groove.

40 In testimony whereof, I have signed my name to this specification.

CHARLES HENRI CLAUDEL.
